The Hartford Carpet Company of Hartford, Ct.
Letters Patent No. 2119 Dated July 11th 1865
Design for a Carpet pattern

The Schedule referred to in these Letters Patent and making part of the same.

To all whom it may concern.

Be it known that I, Henry G. Thompson of the City, County and State of New York, have invented and produced a new and original Design for a Pattern to be wrought into two-ply drugram and other carpeting, in colors similar to those painted on the drawings accompanying this Specification, or in other colors substituted in place of those painted on the drawings herewith; and I do hereby declare that the drawings accompanying this Specification do give and convey to any one skilled in the Art of Carpet weaving a more defined and thorough description of the nature of my invention than it is in the power of language otherwise to convey, and is sufficient to enable any one skilled in the art of carpet weaving to use my invention.

What I claim as my invention and desire to secure by Letters Patent, is the configuration of the Design herewith annexed, when made by being wrought into two-ply drugram or other carpeting, in the form similar to the drawings accompanying this Specification.
